UNITED STATES PATENT OFFICE.

JOHN J. MESSERLI, OF KINGSVILLE, TEXAS, ASSIGNOR OF ONE-HALF TO FREDERICK H. EICKHOFF, OF KINGSVILLE, TEXAS.

AIR-PUMP.

1,140,699.

Specification of Letters Patent. Patented May 25, 1915.

Application filed August 21, 1913. Serial No. 786,023.

To all whom it may concern:

Be it known that I, JOHN J. MESSERLI, a citizen of the United States, residing at Kingsville, in the county of Nueces and 5 State of Texas, have invented certain new and useful Improvements in Air-Pumps; and I do hereby declare the following to be a full, clear, and exact description of the invention, such as will enable others skilled 10 in the art to which it appertains to make and use the same.

My invention relates to improvements in air pumps and especially that class adapted for the inflation of pneumatic tires or for 15 other purposes.

An important object of my invention is to provide a pump of the above mentioned character which in operation is capable of compressing at each stroke of the piston or 20 plunger a quantity of air or other fluid of a volume greater than that which is ordinarily compressed at each stroke of pumps of the usual construction.

A further important object of my invention resides in the provision of a plunger or piston novelly arranged and constructed 25 to provide the desired action.

A still further object of my invention is to provide a device of the above mentioned 30 character which is comparatively simple and inexpensive in its construction and therefore more commercially desirable than pumps at present on the market.

The above and additional objects are accomplished by such means as are illustrated 35 in the accompanying drawings, described in the following specification and then more particularly pointed out in the claims which are appended hereto and form part of this 40 application.

With reference to the drawings, wherein, I have illustrated the preferred embodiment 45 of my invention as it is reduced to practice, and throughout the several views of which, similar reference numerals designate corresponding parts: Figure 1 is a vertical sectional view illustrating my device in assembled operative position, Fig. 2 is a sectional view taken on line 2—2 of Fig. 1 illustrating 50 the transverse pin extending through the lower portion of the pump cylinder and employed for pivotally mounting the foot rest, and Fig. 3 is a detail view of the foot rest.

Referring now to the drawing the number 55 1 designates the pump cylinder which

is formed of any suitable length and diameter and is threaded at its lower terminal to a base cap 2 through which is mounted transversely a pin 3 having eyelets 4 formed at each end and adapted for pivotally supporting the foot rest 5 which may be folded in an out of the way position as indicated by the dotted lines in Fig. 1. The pin 3 also extends through the lower terminal of the pump cylinder 1 as will be clearly seen with 60 reference to Fig. 2, whereby the cylinder is locked in engagement with the base cap 2.

A flanged cap 6 is threaded upon the upper terminal of the pump cylinder 1 and is provided with an air admission port 7 65 formed therein and communicating with the interior of the pump cylinder 1. A piston or plunger designated 8 as an entirety is mounted within the pump cylinder 1 and is threaded upon the lower terminal of a piston rod 9 which extends upwardly through the flanged cap 6 and is provided upon its upper terminal with a suitable handle 10 to be gripped by the operator for the purpose of 70 operating the pump.

An air outlet port 11 is formed through the base cap 2 and lower terminal of the pump casing 1 and is adapted to have connected therewith a suitable hose or pipe, not shown, to supply the air to the article to 75 be inflated.

The piston or plunger 8 in which my invention resides mainly, consists of a flanged tubular portion 12 threaded at its upper terminal to the lower terminal of the piston rod 9 which is provided with an air passage 13 communicating with the interior of the tubular portion 12 at its lower terminal and with the interior of the pump cylinder at its upper terminal through the opening 14 80 formed in the upper terminal of the tubular portion 12. An annular metallic washer plate 15 is mounted upon the tubular portion 12 and engages the under face of the flange 16 formed on the tubular portion. A cup-shaped packing washer 17 is also mounted upon the tubular portion 12 and engages the adjacent face of the washer plate 15 and as a means for retaining the washer 17 in its cup-shaped position this invention employs 85 a cup shaped ring 19 which is mounted upon the tubular portion 12, engages the washer 17 and is held in position by means of a nut 20 which is threaded upon the lower terminal of the tubular portion 12.

110

A plug 21 is threaded interiorly of the lower terminal of the tubular member 12 and disposed at its upper terminal in spaced relation to the lower terminal of the piston rod 9 thereby affording a valve operating chamber 22. The plug 21 is provided longitudinally with the air passage 23 and is grooved transversely as at 24 at its upper terminal to provide for the escapement of the air to the lower part of the pump casing, when the ball valve 25 is seated upon and closes the air passage 23 as will be clearly seen with reference to Fig. 1 in which the ball 25 is illustrated in the position above described. The ball 25 is normally in engagement with the upper terminal of the air passage 23 and will seat upon the valve seat 26 provided by the lower terminal of the air passage 13 in the piston rod 9, when the plunger is moved on its downward stroke, in a manner which will be hereinafter more fully described.

In operation, assuming the plunger to be in a position as illustrated in Fig. 1, it is moved upwardly and air which will have entered the pump casing through the port 7 at the top thereof will pass through the opening 14, port 13, into the chamber 22 about the ball 25 through the groove 24 into passage 23 from thence to the pump cylinder. Upon the downward stroke of the plunger the air which is in the pump cylinder 1 below the piston or plunger 8 will be compressed, and the ball 25 forced in engagement with the valve seat 26 whereby the air will be confined to the lower portion of the pump casing 1 as it is prevented escapement through the passage 13. When the piston or plunger 8 is moved downwardly the air will escape from the pump cylinder 1 through the exhaust port 11. It will thus be seen that I have provided a pump which is arranged and constructed to accomplish the functions hereinbefore described and will owing to its

construction and arrangement of parts, produce a great volume of air.

In reduction to practice, I have found that the form of my invention, illustrated in the drawings and referred to in the above description, as the preferred embodiment, is the most efficient and practical; yet realizing that the conditions concurrent with the adoption of my device will necessarily vary, I desire to emphasize the fact that various minor changes in details of construction, proportion and arrangement of parts may be resorted to, when required, without sacrificing any of the advantages of my invention, as defined in the appended claims.

Having thus described my invention, what is claimed is:

1. In an air pump, the combination with a pump cylinder, of a detachable cap forming a closure for the lower end of said cylinder, a pin rotatably journaled in said cap and having eyelets formed upon its ends, a foot rest slidably supported by said eyelets for movement transversely to or parallel with said cylinder.

2. In an air pump, the combination with a pump cylinder, of a detachable cap forming a closure for the lower end of said cylinder, a pin rotatably journaled in said cap and having eyelets formed upon its ends, a foot rest slidably supported by said eyelets for movement transversely to or parallel with said cylinder, said cylinder being provided with transverse openings near the base thereof, said pin extending through said openings for locking said cap against rotation upon said cylinders.

In testimony whereof I affix my signature in presence of two witnesses.

JOHN J. MESSERLI.
